Primary Examiner — Keith J Wilson(74) *Attorney, Agent, or Firm* — Wood Herron & Evans LLP(57) **CLAIM**

The ornamental design for a personal enclosure, as shown and described.

DESCRIPTION

FIG. 1 is a perspective view of personal enclosure, showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line showing of the claim is included for the purpose of illustrating portion of a personal enclosure and forms no part of the claimed design.

1 Claim, 7 Drawing Sheets(56)
